THERMIONIC TUBES AND THE MANUFACTURE THEREOF

Frederick S. McCullough, Ontario, Canada; The Union National Bank of Pittsburgh executor of said Frederick S. McCullough, deceased

Application June 19, 1933, Serial No. 676,418

5 Claims. (Cl. 250—27.5)

This invention relates to thermionic tubes and to an improvement in the manufacture of such tubes and is for an improvement on the invention disclosed in my co-pending application 5 Serial No. 571,578, filed October 28, 1931, now Patent Number 1,991,767, February 19, 1935.

According to the present invention there is provided a thermionic tube construction in which the envelope of the tube is formed principally 10 of metal. Moreover, there is provided a tube which is complete after it comes off the exhaust pump and does not have to be fitted with a base or cap. Moreover, the tubes may be constructed entirely without any glass, and the 15 usual tubulation for exhausting the tube is not required.

Such tubes can be commercially constructed in very small sizes and yet perform the same work as the usual glass tube many times its size, 20 and they are particularly suited to the demand for an inexpensive tube which requires little space.

The present invention also provides a novel method in the manufacture of such tubes, and 25 more particularly in the method of sealing the tubes while the tubes are being exhausted, and without the usual glass tubulation. It further provides a novel arrangement for protecting certain portions of the tube from overheating while 30 other portions are being heated to a high temperature for driving out the gases.

The invention may be readily understood by reference to the accompanying drawing which 35 illustrates one embodiment of my invention and in which:

Figure 1 shows a vertical section through a tube and exhaust hose connection prior to the sealing of the tube;

Figure 2 is a similar view after the tube has 40 been sealed; and

Figure 3 is a front elevation of a complete tube embodying my invention, and the drawing shows on a full sized scale a commercially practical size tube embodying the present invention 45 and capable of doing the same work as the common commercial radio tube now generally employed.

It will be seen by reference to Figs. 1 and 2 50 that these views are on a much larger scale than the full sized scale of Fig. 3.

Referring first to Fig. 1, the envelope of the tube is comprised principally of a piece of metal tubing 2 of a suitable diameter and of a suitable length. Nickel, or a nickel containing alloy, 55 is preferably used for this purpose. When a

piece of tubing 2 has been provided, a ceramic base member 3 is fitted into the lower end of the tubing. Passing through this base member 3 are three contact pins 4, 5, and 6. The inner end of the contact pin 4 supports a grid electrode 5 1. The inner ends of the pins 5 and 6 are connected to a heater wire 8, which wire is supported in an insulator 9 inside a metal sheath or sleeve 10, the sheath or sleeve comprising the cathode of the tube. Preferably, these electrodes are assembled on the insulator 3 before the insulator is inserted into the envelope 2. After the insulator has been inserted in the envelope, it is sealed in place. This sealing may be accomplished, if the material 3 is a low melting point 15 ceramic material, by heating the end of the tube and fusing the ceramic material directly to the metal, at the same time fusing the ceramic material around the pins 4, 5 and 6. If, however, the base 3 is of a high temperature ceramic 20 material, it may be sealed in place by flowing a low melting point fusible material 11 into the open end of the tube 3 over the bottom of the insulator 3 and around the pins 4, 5 and 6. In either event, a gas-tight seal is formed at the 25 end of the tube.

Leading from the top of the cathode 10 is a wire 12. Inserted into the upper end of the tube 2 is an insulator 13 similar to the insulator 3, but having a central opening 14. This insulator has a close fit in the tube and may be of a low fusing ceramic material sealed into the upper end of the tube by fusing it to the metal, or it may be sealed in place by the use of a low fusing ceramic substance. The cathode lead 30 wire 12 passes up through the opening 14 and is preferably made long enough to project a considerable distance beyond the end of the tube.

When the structure has been assembled this 40 far, it is ready to be exhausted and sealed. For this purpose a gob of low fusing ceramic material 15 is placed about the wire 12, and the upper end of the tube is forced into the end of a thick rubber tubing 16 leading to an evacuating pump 45 (not shown). Inside the tube 16 there is fitted a coil having an upper portion 17 of relatively larger diameter and relatively larger wire, this part of the coil having a frictional engagement with the inside of the tube 16. Connected onto the lower end of the upper portion of the coil is a lower portion 18 of relatively less diameter and of relatively smaller wire, the turns 18 being out of contact with the interior walls of the tube. The lower end of the turns 18 and the 50 upper end of the turns 17 are connected together 55

so that the coil forms a short-circuited loop. The low fusing ceramic material 15, when the tube is inserted in the rubber tubing, lies closely within the turns of the wire 18.

5 Below the end of the tubing 16 are two spaced apart cooling rings 19 and 20, the upper cooling ring 19 surrounding the upper portion of the tube 2 adjacent the disc 13 and the lower ring 20 surrounding the lower portion of the tube just above 10 the disc 3. Between the rings 19 and 20 is a coil 21 connected in circuit with a high frequency oscillator 22. Surrounding the end of the hose 16 is another coil 23 which is connected in circuit with a source of high frequency alternating current, such as an oscillator 24.

15 After the tube has been exhausted for a predetermined time, it is inductively heated by the passage of a high frequency current through the coil 21 to drive out additional gases. In this process of inductive heating the envelope 2, of course, becomes quite highly heated as well as do the electrodes within the tube. The cooling rings 19 and 20 cool those portions of the envelope adjacent the ceramic discs 3 and 13 to protect these 20 discs from melting if they are formed of a low fusing material, or to protect the low fusing material which seals them in place. This is course is accomplished by the circulation of a cooling fluid through the cooling rings 19 and 20. After 25 the tube has been based in this fashion it is ready to be sealed. To seal the tube a high frequency current is passed through the coil 23. This induces current in the coil 17-18, and the small wires 18 of this coil are heated to a point where 30 they cause the low fusing ceramic material 15 to melt and flow down the wire into the opening 14. This material may spread out over the top of the disc 13, or it may merely plug the hole 14. In order to prevent the material from flowing entirely through the opening 14, a small metal shield 25 is preferably secured to the wire 12 just below the opening 14 while the tube is being assembled. When the fused material 15 flows down into the opening 14, it cools and thereupon 45 seals the tube and the tube can be taken off the pump. When it is taken off it is a complete tube, the pins 4, 5 and 6 providing the base pins, so that no further base is provided. The wire 12 provides the cathode lead, and the metal shell 50 tube comprises the plate of the tube and connection can be made directly to this tube.

55 The entire operation and assembly for pumping and sealing the tube can be carried out very rapidly, and the time required for pumping and baking is very much reduced by reason of the smaller volume of the envelope than where there is a relatively large glass envelope. The sealing of the tube is simplified because there is no tubulation which has to be compressed, and the completed tube is one which is very rugged, there being no thin glass in the construction either in the form of a tubulation or in the form of an envelope. It will be obvious to those skilled in the art that where additional electrodes are required these can be put into the assembly. It will 60 also be understood that while the invention has particular application to the construction of small relatively inexpensive tubes, the invention is not limited to the manufacture of such tubes, but is also preferable to the manufacture of large tubes for various purposes.

70 It will be understood, however, that the drawing is merely illustrative of the invention and that various changes and modifications may be made in the construction and arrangement of

the various parts within the contemplation of my invention and under the scope of the following claims.

I claim:

1. A thermionic tube comprising a cylindrical metal shell of substantially uniform diameter having a non-metallic base member sealed therein in adjacent one end thereof and having contact pins passing therethrough and sealed therein, an indirectly heated cathode inside the tube having a heater wire connected to two of said contact pins, another electrode inside the tube connected to another of said contact pins, an insulating disc sealed into the opposite end of the tube and having a passageway therethrough, a cathode lead wire passing through said passageway and connected to said indirectly heated cathode, and a mass of sealing material fused about said cathode wire and into the passageway in the disc. 15

2. In the manufacture of vacuum tubes, the method which comprises assembling electrodes within a metal shell, providing an insulating disc having an opening therethrough at one end of said shell, connecting said end of the shell with a conduit leading to a vacuum pump to evacuate 25 the tube, and then melting fusible sealing material in the conduit whereby such material flows over the opening in said insulator and effectively seals the tube.

3. In the manufacture of vacuum tubes, the steps which comprise assembling electrodes inside a metal shell which is sealed at one end, sealing a ceramic wall member into the opposite end, the wall member having an opening therein, connecting the shell with a vacuum pump in such manner that the tube may be evacuated 35 through the opening in said wall member, and then fusing a gob of low melting material to said ceramic wall member over said opening and while the tube remains connected with the vacuum 40 pump.

4. In the manufacture of vacuum tubes, the steps which comprise assembling electrodes inside a metal shell on a base of insulating material forming a closure for one end of the shell, 45 sealing such base to the metal shell by the use of a fusible material, partially closing the other end of the shell by a disc having an opening therethrough and sealing such disc to the metal through the use of a fusible material, connecting 50 said last mentioned end of the tube with a conduit leading to an evacuating pump, evacuating the tube, heating the tube to an elevated temperature to drive out heated gases and simultaneously cooling those portions of the tube which are adjacent the base and said disc, and thereafter flowing fused sealing material into the opening in said disc while the tube remains connected with the pump. 55

5. The method of making a thermionic tube 60 having an envelope, comprising a metal shell which comprises mounting a number of electrodes on a common supporting member, providing a metal envelope having a bushing in its upper end, introducing the base member with the electrodes thereon to the bottom of the metal envelope in such manner that an upwardly extending wire projecting upwardly from the electrode assembly passes through said bushing sealing the base member to the envelope to make an air-tight joint, and sealing a gob of fusible material into the end of said bushing around said wire. 70
